UNITED STATES PATENT OFFICE

104,266

DESIGN FOR A TEXTILE FABRIC OR SIMILAR ARTICLE

Adolph C. Jaeger, Port Chester, N. Y.

Application February 19, 1937, Serial No. 67,742

Term of patent 7 years

To all whom it may concern:

Be it known that I, Adolph C. Jaeger, a citizen of the United States, residing at Port Chester, county of Westchester, State of New York, have invented a new, original, and ornamental Design for a Textile Fabric or Similar Article, of which the following is a specification, reference being had to the accompanying drawing which forms a part thereof, and in which I have shown several units of the design.

It will be noted that this is an all-over design, and the same group of figures is repeated in both directions.

I claim:

The ornamental design for a textile fabric or similar article substantially as shown and described.

ADOLPH C. JAEGER.
